UNITED STATES PATENT OFFICE

ALFRED VAN DE SANDT, OF LOS ANGELES, CALIFORNIA

STONE BUFFER

Application filed February 27, 1926. Serial No. 91,123.

With the present generally known method of applying finish to stone; namely, that in which the disc is used and disposed face downward, a perfectly flat surface is necessary to obtain satisfactory results. The present method is, therefore, defective for general application except in rare cases. Since the texture of the stone varies in spots and the polishing disc employed is inflexible, low spots or slight depressions cannot effectively be reached and what polish is secured by the method is produced by burnishing, later causing corrosion, particularly in white marble.

It is a purpose of the present invention, therefore, to provide a construction in which the rubbing surface of the polishing element may change in accordance with and to conform to irregularities of contour in the stone being operated upon; to provide a construction in which the even pressure necessary to effect the best results is had, so that slight depressions or hollow sections may be reached; and to provide a construction consisting of rotary polishing elements susceptible, when in use, of changes in configuration both peripherally and axially.

With this purpose in view, the invention consists in a construction and combination of parts of which a preferred embodiment is illustrated in the accompanying drawings, wherein:

Figure 1 is a side elevational view of the invention.

Figure 2 is a top plan view.

Figures 3, 4 and 5 are respectively sectional views on the planes indicated by the lines 3—3, 4—4 and 5—5 of Figure 2.

In the illustrated embodiment of the invention, the buffing or polishing elements consist of the cylindrical rolls 10 carried by a frame 11 simulating the general form of a pair of scissors. The sections of the frame are pivotally connected by means of a rock shaft 12 and the rolls have a bodily movement in an arc with the rock shaft as a center, being impelled toward each other by means of the springs 14 coiled around the protruding extremities of the rock shaft and terminally secured to the elements of the frame, the connections between the springs and the frame

consisting of posts 15 on the sections or elements of the latter, said posts being provided with transverse eyes in which the extremities of the springs have sliding engagement. Collars 16 are secured to the rock shaft and serve to retain the coiled portions of the spring in position thereon and serve also to retain the rock shaft in the frame.

The polishing or buffing rolls are susceptible of flexion both peripherally and axially due to their construction specifically defined later on. Because of this feature, all portions of the stone surface being polished are readily reached with the peripheral faces of the rolls and the springs 14 function to maintain even pressure when the handles 17 are grasped by the operator, the illustrated form of the invention being designed for hand operation. Each element of the frame carries one of the handles and downward pressure upon them, when the rolls are in contact with the stone, tends to move the rolls away from each other, but at the same time pressure is being applied upon the stone and because of the character of the rolls, all irregularities in surface contour are reached by the polishing surface.

The elements or sections of the frame each consists of the opposed side bars 18 to which the handle bars 19 are secured, the bars 18 and 19 being disposed at an acute angle. The bars 19 are longer than the bars 18 and thus the handle 17 associated with each roll is disposed in a vertical plane outside of the vertical plane of the latter. By means of this arrangement, the hand pressure of the operator, due to the increased leverage afforded by the position of the handles, is less than the pressure exerted by the rolls upon the surface being polished. The rolls are journalled in the extremities of the bars 18 and motion is communicated to them in any acceptable manner. In the present embodiment, a flexible shaft 20 connects the two rolls on one side of the frames and one of the rolls on the opposite side is provided with a protruding stub shaft 21 with which a driving means may be connected. This also may be of any acceptable form but would preferably be a flexible shaft connected with a driving motor, neither of which is illustrated here as the

particular form of driving means is not essential to the successful operation of the invention.

In order that the polishing rolls may be fixed, bent or distorted axially, they are carried by flexible shafts which, in the present form of the invention, consist of telescopically related reversely wound spiral springs 22 and 23 of which the latter is interior to the former. Both, however, connect with the end discs 24 formed with stub shafts 25, the latter constituting the journals in the bars 18 of the frame sections and certain ones being extended for connection with the flexible shaft 20 while the extension of another constitutes the stub shaft 21. The connections between the discs and the springs consist of annular flanges 26 and 27 formed on the inner faces of the discs and defining cylindrical seats for the extremities of the springs which are secured to the discs in these seats in any acceptable manner. In surrounding relation to the shafts consisting of the springs 22 and 23 there is disposed an interior cushion 28 of readily yielding material, such as rubber, and bounding this cushion there is a more flexible cushion 29 made hollow for the reception of a fluid, such as water or air under pressure, this latter cushion carrying the buffing or peripheral polishing element 30 which may, if desirable, be provided with bristles or which, as shown, may be a suitable fabric chemically treated.

It is obvious that, with the polishing rolls constructed along the plan indicated, they become conformable to irregular contours in the direction of their length as well as peripherally and consequently the rolls become effective for applying the desired polish to all the surface of the stone being operated upon, the bottoms of grooves, high points, ridges and depressions as effectively as the even surface.

The invention having been described, what is claimed as new and useful is:

1. A stone polishing roll bodily bendable axially between its extremities.
2. A stone polishing roll having a distortable buffing face and being bodily bendable axially between its extremities.
3. A stone polishing roll having a peripheral or buffing surface, a fluid cushion immediately behind said surface, and a shaft extending through and supporting said roll at separated points within the roll and being flexible between the points.
4. A stone buffing roll provided with a peripheral buffing surface, and a shaft extending through said roll and supporting the latter, the roll and that portion of the shaft within the roll being flexible.
5. A stone buffing roll provided with a peripheral buffing surface, a shaft extending through the roll and supporting the latter, that portion of the shaft comprehended be-

tween the ends of the roll being flexible, a cushion of yielding material surrounding and enclosing the flexible portion of the shaft, and a fluid cushion interposed between the first said cushion and the buffing surface.

6. A stone buffing roll provided with a peripheral buffing surface, a shaft extending through the roll and supporting the latter and consisting of telescopically related spiral springs terminating at the ends of the roll, a cushion of yielding material surrounding and enclosing said shaft, and a fluid cushion interposed between the first said cushion and the buffing surface.

7. A stone buffing roll provided with a peripheral buffing surface, end disks of less diameter than the roll at the buffing surface, said end disks being provided with stub shafts constituting journals, a flexible shaft within the roll and consisting of reversely wound telescopically related spiral springs connected with the end disks, a cushion of yielding material enclosing said shaft and a fluid cushion interposed between the first said cushion and the buffing surface.

In testimony whereof he affixes his signature.
